FIG. 2.

UNITED STATES PATENT OFFICE

JOHN E. ALBERTOLI, OF SAN FRANCISCO, CALIFORNIA, ASSIGNOR TO SPRAGUE-SELLS CORPORATION, OF HOOPESTON, ILLINOIS, A CORPORATION OF DELAWARE

EXHAUST BOX

Application filed October 9, 1923. Serial No. 687,500.

My invention relates to devices used in the canning industry for heating the cans after filling and before capping so as to exhaust the imprisoned air from the contents 5 of the can.

One of the objects of the invention is to provide an exhaust box capable of accommodating a very large number of cans relative to the floor space it occupies.

10 Another object of the invention is the provision of an exhaust box embodying a disk conveyor in which one side of the disks effects the movement of the cans in one direction and the opposite side of the disks 15 effects the movement of the cans in the other direction.

My invention possesses other objects and features of advantage, some of which, with the foregoing, will be set forth in the following description of the preferred form of my invention which is illustrated in the drawings accompanying and forming part of the specification. It is to be understood that I do not limit myself to the showing made by 25 the said drawings and description, as I may adopt variations of the preferred form within the scope of my invention as set forth in the claims.

Referring to the drawings:

30 Figure 1 is a plan view of my exhaust box with the cover omitted and certain portions broken out to disclose the structure, and to shorten the length of the figure.

Figure 2 is a vertical elevation taken in 35 a plane indicated by the line 2-2 of Figure 1.

The exhaust box of my invention comprises a casing 2 which forms the housing thru which the cans pass in order to be heated. The casing is supported on a suitable frame-work 3 and is provided with a cover 4. Disposed within the casing is a plurality of rows of disks 5, each of which is arranged above, and concentric with, a spur gear 6, 40 both disk and gear being fixed upon a vertical stub shaft 7, journaled in a thrust bearing 8. Cross bars 9 extending longitudinally thru the inside of the casing provide support for the bearings. Each of the bearings 45 is formed with an oil reservoir 11, fed thru

the supply pipe 12, and a spiral groove on the shaft carries the lubricant over the face of the bearing.

The gears 6 in each row are connected by gears 13 having their axes parallel to and disposed in the same vertical plane as the axes of the related gears 6. The gears 13 are each provided with a shaft, and are journaled in bearings in a manner similar to the gears 6. The shaft 15 of one of the gears 13, 55 in each row, is arranged in a bearing 16, and extends downwardly thru a second bearing 17, supported on the horizontal members of the frame 3, and is provided at its end with a bevel gear 18, in mesh with a similar bevel 60 gear 19, fixed on the drive shaft 21. The drive shaft which extends transversely across the machine, is journaled in suitable 65 bearings 22 supported on the frame of the machine and is driven by a pulley 23 connected to any suitable source of power. Thus rotation of the shaft 21 is communicated to each row of disks, all of which as 70 will be noted, revolve in the same direction, as indicated by the arrows in Figure 1. An 75 oil supply pipe 24 connected into the upper part of each bearing 16 supplies lubrication for the shaft 15.

Means are provided for heating the box, 80 comprising steam pipes 26 suitably apertured to permit steam to flow into the box therefrom. The steam pipes extend longitudinally of the casing between and above the rows of disks, and are fed from a header 27 at one end of the exhaust box. A bracket 28, 85 extending upwardly from the frame of the machine, supports the steam pipes, and at the same time, plates 29, so shaped as to complement the curve of the periphery of the disk, 90 as shown in Figure 1. These plates 29 serve as guides to prevent the cans on the disks working off of the disks and falling between them, and it is to be noted that the pipe 26 also performs a similar guiding function, that is to say, both the steam pipes 26 and the plates 95 29, act to retain the cans on the disks in the event that there is any tendency on the part of the cans to work off of the disk. Similar guide plates 31 are disposed on the side of the casing. 100

Means are also provided for forcing the cans to travel up one side of the row of disks and down the other side, and such means comprises a straight guide rail 32 supported on the cross rails 33, and extending across the end disks in each row. Thus cans carried around on one disk strike the guide rail 32, and are worked over to the next succeeding disk, then carried by this disk thru approximately 180°, when they again strike the guide rail and are worked over to the next succeeding disk and so on, until the last disk of the row is reached, where the can is carried almost completely around the disk and starts on the return journey on the opposite side of the guide rail. When on the return journey, the can reaches the first disk once more, but on the opposite side to that on which it entered the disk, it strikes the guide rail 34 and is worked over to the first disk of the next row in which it travels as before, up one side of the row of disks and down the other.

Because it is advisable to deliver the cans at the end of the machine opposite to that in which they are received, it may be necessary, as shown in Figure 1, to make no use of one side of the last row of disks, the cans passing from the discharge side of the first disk of the next to the last row to the receiving side of the first disk of the last row, and then traveling up the inside of the last row, and being discharged from the box as shown in Figure 1. Of course, it is obvious without special illustration, that both sides of each of the rows may be utilized by taking the cans from the filling machine upon a conveyer which will carry them to the far side of the exhaust box, that is, the same side from which the cans are discharged.

As shown, the exhaust box is provided with an entrance aperture 36 through which the cans are fed on to the first disk 5, from feed disks 37 and 38, which are mounted in a manner similar to the disks 5 and driven in the same way by the gears 39, similar to the gears 6 and similarly mounted. A guide rail 41 extends thru the center of the two disks 37 and 38 and connects with the guide rail 32 within the casing, and a guide rail 42 extends from the casing around the periphery of the feed disk 37 as shown. A table 43 adjacent the feed disks, receives the sealed can from the syruping machine.

At the opposite end of the exhaust box is the discharge aperture thru which the exhausted cans pass upon the disk 44, from which they pass to disk 46 and then to the table 47. Disks 44 and 46 are driven, respectively, by gears 51 and 52 similar to the gears 6 and similarly mounted.

I claim:

1. An exhaust box for cans comprising a casing, a row of tangentially arranged disks in said casing, means for rotating said disks, and means for guiding articles to be conveyed over said group first on one side of the center of each successive disk in the group and then on the opposite side of each successive disk in the reverse order.

in the same direction, and means disposed adjacent said disks to guide the cans thereon up one side of said row of disks and down the other side.

2. An exhaust box comprising a casing, a row of tangentially arranged disks in said casing, means for rotating said disks in the same direction, a straight guide rail overlying said disks and extending between the centers of the end disks, and guide means arranged at the periphery of said disks. 75

3. An exhaust box comprising a casing, a row of tangentially arranged disks in said casing, means for rotating said disks in the same direction, and a straight guide rail 80 overlying said disks and extending between the centers of the end disks.

4. An exhaust box for cans comprising a casing, a plurality of rows of tangentially arranged disks in said casing, means for rotating said disks in the same direction, a straight guide rail overlying each row of disks and extending between the centers of the end disks, and guide means for directing cans from the delivery side of the end disk of one 85 row to the receiving side of the end disk of the adjacent row. 90

5. An exhaust box for cans comprising a casing, a plurality of rows of tangentially arranged disks in said casing, means for rotating said disks in the same direction, a straight guide rail overlying each row of disks and extending between the centers of the end disks, guide means for directing cans from the delivery side of the end disk of one row 95 to the receiving side of the end disk of the adjacent row, and guide means comprising steam pipes for heating the box disposed between the rows. 100

6. An exhaust box for cans comprising a 105 casing, a plurality of rows of tangentially arranged disks in said casing, means for rotating said disks in the same direction, a straight guide rail overlying each row of disks and extending between the centers of the end disks, guide means for directing cans from the delivery side of the end disk of one row 110 to the receiving side of the end disk of the adjacent row, guide means comprising steam pipes for heating the box disposed between 115 the rows, and guide means extending along the periphery of the disks mounted on said pipes.

7. A conveyor comprising a group of tangentially arranged disks, means for rotating said disks, and means for guiding articles to be conveyed over said group first on one side of the center of each successive disk in the group and then on the opposite side of each successive disk in the reverse order. 120

8. A conveyor comprising a group of tangentially arranged disks, means for rotating said disks, and means for guiding articles to be conveyed over said group first on one side of a line determined by the centers of two 130

of the disks and then on the opposite side of said line to a point adjacent the starting point.

9. A conveyor comprising a group of tangentially arranged disks, means for rotating said disks, and means for guiding articles to be conveyed over said group first in one direction on one side of a line determined by the centers of two of the disks and then back-
wardly to the starting disk on the opposite side of said line.

10. A conveyor comprising a group of tangentially arranged disks, means for rotating said disks, and guide means for permitting objects on said disks except the terminal disk to be moved from one disk to the next by the rotation of the disk thru less than one-half turn.

11. In testimony whereof, I have hereunto set my hand.

JOHN E. ALBERTOLI.
